UNITED STATES PATENT OFFICE.

HENRY SJOVIK, OF GREAT FALLS, MONTANA.

IDENTIFICATION-SIGN.

1,027,008.

Specification of Letters Patent.

Patented May 21, 1912.

Application filed November 4, 1910. Serial No. 590,712.

To all whom it may concern:

Be it known that I, HENRY SJOVIK, a citizen of the United States, residing at Great Falls, in the county of Cascade, State of Montana, have invented certain new and useful Improvements in Identification-Signs; and I do hereby declare the following to be a full, clear, and exact description of the invention, such as will enable others skilled 10 in the art to which it appertains to make and use the same.

This invention relates to identification signs for street corners, houses, vehicles.

The object of the invention is to provide 15 a sign having removable designation characters which may be changed from time to time as necessary, and further having these designation characters spaced from the support to which the sign may be attached so 20 that rainwater and the like will not gain access to the characters.

With the above object in view the invention consists of the novel details of construction and combination of parts herein- 25 after fully described and claimed, it being understood that various modifications may be made in the minor details of construction within the scope of the appended claim.

In the accompanying drawing forming 30 part of this specification, Figure 1 is a front elevation of a sign constructed in accordance with my invention. Fig. 2 is a cross sectional view taken on the line 2—2 Fig. 1. Fig. 3 is a longitudinal sectional view taken 35 on the line 3—3 Fig. 1. Fig. 4 is a plan view of the blank from which the sign supporting frame is formed.

Referring now to the drawing in which like characters of reference designate similar parts, the sign is seen to comprise a supporting frame 10 formed from a single plate of pliable material. The plate is provided centrally with a longitudinal orifice 11, and is provided in its edges adjacent to the ends 45 of this orifice with spaced notches 12, the material between these notches being curved backwardly and then inwardly to form mirror receiving grooves 13, and the material intermediate these notches and ends of the 50 plate forming tabs which are bent so as to

close the ends of the grooves as shown at 13, thence being extended in the planes of the closed ends a distance approximately equal to the shortest diameter of the closed ends, thence being bent abruptly at right angles 55 upon themselves and forming supporting lugs 14, the free legs of these lugs being arranged in a plane parallel to the plane of the plate so that when the sign is applied, the identification plate in said grooves will 60 be spaced from the support to which the device is attached so that rainwater and the like will not gain access to the identification plate.

Arranged in the grooves of the frame are 65 a plurality of juxtaposed mirrors 15, these mirrors by virtue of the tabs or supporting lugs of the frame being pliable, being bodily removable from the frame at any time as may be necessary. Each mirror is 70 provided with an identification character, and in order that the identification character may be more readily visible at night than ordinary signs said character is formed by scraping a corresponding portion of the 75 light reflecting element from the mirror and this scraped portion covered with an opaque element 17 such as black paint or the like. The identification character thus formed is disposed in the reflecting field which will cause 80 the character to stand out in relief when the sign is viewed from a certain angle, and it is clear that a pedestrian may by shifting its position at night readily view the sign from such an angle as to make all the characters 85 stand out in relief. For retaining the characters against displacement from the frame should they be broken, a metal back piece 18 is secured in the mirror receiving grooves of the frame, and forms an abutment against 90 which the mirrors rest.

What is claimed is:

A sign including a one piece frame formed from a single blank of pliable material having a longitudinal opening, the longitudinal 95 portions of said blank being bent backwardly and then inwardly to form sign receiving grooves, the end portions of said blank being bent to form straight legs which close the ends of said grooves and extend in 100

the planes of said closed ends for a distance equal to approximately the shortest diameter of the closed ends whereby to space the frame from the support to which it may be applied, said legs being terminally bent outwardly to form securing lugs, and an identification element secured in said grooves, and exposed through said longitudinal opening.

In testimony whereof, I affix my signature, in presence of witnesses.

HENRY SJOVIK.
